UNITED STATES PATENT OFFICE

133,819

DESIGN FOR A DANCE SLIPPER

Leo Harris, Chicago, Ill.

Application July 25, 1942, Serial No. 107,678

Term of patent 7 years

To all whom it may concern:

Be it known that I, Leo Harris, a citizen of the United States, residing at Chicago, in the county of Cook and State of Illinois, have invented a new, original, and ornamental Design for a Dance Slipper, of which the following is a specification, reference being had to the accompanying drawing, forming part thereof.

In the drawing,

Fig. 1 is a side view of a dance slipper showing my new design;

Fig. 2 is a top plan view thereof; and

Fig. 3 is an end view of the heel portion of the slipper.

I claim:

The ornamental design for a dance slipper, as shown.

LEO HARRIS.
